UNITED STATES PATENT OFFICE

OLIVE F. STENGEL, OF ROCKVILLE, CONNECTICUT

SANITARY SEALING DEVICE FOR MILK BOTTLES

Application filed December 23, 1927. Serial No. 242,216.

This invention relates to a sanitary sealing device for milk bottles and the like and more particularly to a cap for application to milk bottles, which will completely cover not only the ordinary milk bottle cap, but likewise the mouth of the bottle, so that the same is protected against contamination in handling or the like.

An important object of the invention is to provide a device of this character, which may be very readily and cheaply produced, may be easily applied to the bottle and will fully perform the functions for which it is intended.

15 These and other objects I attain by the construction shown in the accompanying drawing, wherein for the purpose of illustration is shown a preferred embodiment of my invention and wherein:—

20 Figure 1 is a side elevation of the upper end of a milk bottle having a sealing means applied thereto in accordance with my invention;

Figure 2 is a vertical sectional view there-
25 through;

Figure 3 is a bottom plan view of the sealing means.

Referring now more particularly to the drawing, the numeral 10 designates a preferably substantially cylindrical piece of material, which may be formed from paper, cloth or any other suitable medium having integrally connected therewith an elongated tab 11, one surface of which is gummed, as indicated at 12. As previously noted, the body of the device is preferably substantially cylindrical, and where this construction is employed, the tab 11 should have its outer edge 13 tangential to the periphery of the body. In alignment with the inner edge, the body should be notched, as indicated at 14, to a depth equal to the width of the band, so that the band may occupy a position such that it will be perpendicular to the folded edge 15 of the body 10, when the center of the same is placed over the mouth of a milk bottle and the edges thereof are folded against the neck thereof, as shown in Figure 1. With the parts in this position, it is

55 has been previously moistened, about the folded end 15, when the seal will be completed. It will, of course, be obvious that the body 10 need not be circular in form, although this form is preferred, for the reason that it presents the neatest appearance when in applied position. The tab 11, however, to insure proper application thereof should be either perpendicular or substantially perpendicular to a line bisecting the body 10, and 60 the inner end of the notch 14 should extend to a point adjacent such a line. While the body and tab are preferably integrally secured, it will be obvious that this tab could be attached, if so desired.

65 Since the construction hereinbefore set forth is capable of a certain range of change and modification without materially departing from the spirit of the invention, I do not limit myself to such specific structure except 70 as hereinafter claimed.

I claim:

1. A sanitary sealing device for milk bottles and the like comprising a body in the form of a circular sheet adapted to be placed 75 over the mouth of a milk bottle or the like and have its edges folded downwardly about the neck thereof, said body having an integral tab which in the applied position of the body may be wrapped around the folded 80 edges of the body to secure the same in position, the tab having one face thereof gummed, said tab being perpendicular to a bisector of the body, the outer edge of the tab forming a continuation of the peripheral edge of the 85 sheet, the sheet in alignment with the inner edge of the tab being notched.

2. A sanitary sealing device for milk bottles and the like comprising a body in the form of a circular sheet adapted to be placed 90 over the mouth of a milk bottle or the like and have its edges folded downwardly about the neck thereof, said body having an integral tab which in the applied position of the body may be wrapped around the folded edges of 95 the body to secure the same in position, the tab having one face thereof gummed, said tab being perpendicular to a bisector of the body, the outer edge of the tab forming a 100 continuation of the peripheral edge of the

sheet, the sheet in alignment with the inner edge of the tab being notched, said notch being of a depth sufficient to free the periphery of the sheet for the width of the tab.

⁵ In testimony whereof I hereunto affix my
signature.

OLIVE F. STENGEL.
